SECTIONAL DOOR

Le Roy Howard Kiesling, Brooklyn, N. Y.

Application January 24, 1935, Serial No. 3,304

6 Claims. (Cl. 20—20)

This invention relates to sectional doors, and more particularly to the construction of doors composed of horizontal sections articulated to each other and adapted to slide or travel upwardly and inwardly to an overhead position when the door is opened, the reverse movement closing the door downwardly to the floor and against the door jamb.

The general object of the present invention is to improve the construction and operation of sectional doors of the kind referred to. A particular object is to afford a sectional door construction which is inexpensively constructed and assembled, and yet is rugged and durable, and efficient and convenient in operation. Further objects and advantages will be explained in the hereinafter following description of an illustrative embodiment of the invention or will be understood to those conversant with the subject.

20 In the accompanying drawing Figure 1 is a vertical section of a doorway and sectional door embodying the present invention, the door in this figure being shown down and closed against the jamb.

25 Fig. 2 is similar to a portion of Fig. 1 but shows the door shifted upwardly and inwardly to partially open position.

30 Fig. 3 is a horizontal section, taken for example at the line 3—3 of Fig. 1, at one side of the door, the other side being symmetrically similar.

35 Fig. 4 is an interior elevation view of end portions of two contiguous door sections and adjacent mechanical parts.

Fig. 5 is an inside elevation of a part of Fig. 4 on a larger scale.

40 Fig. 6 is a right elevation partly in section on the line 6—6 of Fig. 3.

Fig. 7 is a right elevation and section on the line 7—7 of Fig. 3.

45 Fig. 8 is a section taken on the line 8—8 of Fig. 7.

Fig. 9 is a right elevation of a preferred form of traveling circular head or disk and surrounding tire by which the door sections are guided in their shifting movements.

The door jamb 9 is shown in Figs. 1 and 3. Attached to its corner against which the door closes is preferably an angle iron 10, taking the wear, and from which outstands rigidly a threaded post 20 for a purpose later to be described. The door when closed comes down to a concrete or other floor 11. Above the doorway is indicated a conventional lintel 12, while at the interior are shown overhead or ceiling beams 13.

Inwards of each door jamb 9 is a track 14,

spaced somewhat from the jamb and inclined upwardly away from the jamb to a slight angle, for example as indicated. The incline of the track is relative to the jamb, the two diverging angularly slightly from the floor to the top of the doorway. By this arrangement the door separates from the jamb when sliding up from closed position, and vice versa. Beyond the rising stretch 14 of the track is a curved connecting stretch 15, and therebeyond a substantially horizontal inwardly extending stretch 16 which may be hung from the ceiling beams 13. The entire door may be in engagement with track stretches 15 and 16 when open.

An advantageous track construction is seen in Figs. 1, 2, and 3 wherein the body of the track has at one side a flat outstanding flange 17 and at the other side a concave flange 18, this arrangement facilitating the assemblage and erection of the tracks and door, while properly confining the sliding or rolling elements between the track flanges.

In setting up the structure it is necessary to adjust accurately the position of each track portion 14 in relation to the door jamb. The track 25 is shown mounted on a supporting angle iron 19 which may run longitudinally of the track, and may be duplicated at its overhead stretch. The outwardly extending flange of the angle iron 19 may be formed with perforations or elongated vertical slots to receive a number of threaded posts or bolts 20 located at convenient points along the length of the track, each of these bolts standing out rigidly from the jamb angle iron 19, several inches from the jamb edge. A pair of nuts 21 is shown positioning and locking the angle iron 19 upon the bolt 20. By loosening one nut and tightening the other the angle iron may be shifted inwardly or outwardly until the door is in correct relation to its jamb, namely, preferably 40 in snug contact against the jamb when the door is lowered to its closed position shown in Fig. 1. Loosening the nuts 21 permits tilting of the angle and track to assist entering the sliding element therein.

Coming now to the door, this is shown as composed of a number of horizontally extending sections articulated or hinged to each other, rendering flexible the door. In the illustrated instance four door sections are shown, the first section 22 being at the bottom, with intermediate sections 23 and 24, and a top section 25. The mode of hinging may be as described later or otherwise, either combined with the hanger devices or independent.

The described door is provided with a series of sliding or rolling hanger devices, preferably but not necessarily at least one for each door section. Each hanger device may consist of the following elements. A bearing member 27 is shown mounted at the inner face of the lowest door section 22, near its lower edge, and a similar hanger bearing 27 mounted near the upper edge of the top section 25. The lower edge of each door section 23, 24, and 25 is shown provided with a hanger bearing 28 which may be of different construction from the bearing 27, as the former may afford the hinging of adjacent sections. All of these bearing members 27 and 28 however are shown formed with square openings each to receive a square sleeve 29, the square passage in which in turn contains a horizontal square axle 30 adapted to slide through the sleeve. By square is intended to include any polygonal or other non-round form that cannot rotate.

The several hanger bearings 27 and 28 are constructed similarly in that their dimensions are such as to support each of the hanger axles 30 at the same distance from the inner face or plane of the door, as is clear in Figs. 1 and 2. The several axles have their axes in a common plane parallel to the closed door. By reason of the square hole in the hanger bearings 27 and 28, and the square sleeves therein, the square axles 30 are held against rotation relatively to the door sections. These axles of course for this purpose need be squared or shaped only at the places where they engage the sleeves. The extreme ends of each axle project beyond the sides of the door to support the traveling elements to be described.

At this point will be described a convenient means of hinging or articulating the door sections to each other. While independent hinges might be employed, and the hanger bearings 28 offset therefrom, preferably each such bearing is used as half of a hinge, and the axle 30 as the hinge pivot. The hinge is completed by a complementary half 32, attached, in each case, to the adjacent or upper end of the contiguous or underneath door section. As best shown in Figs. 3, 4, and 5 the hinge part 32 is bifurcated and straddles the hinge part 28; obviously however, these shapes could be reversed. To facilitate rotation of each hinge part 32 on the square axle 30, the ears 33 of said hinge part are shown as each containing a circular lining or sleeve 34, see Figs. 5 and 7. If shapes 23 and 32 be reversed a single round sleeve 34 in member 32 will suffice, confined axially between the spaced ears of member 23 and surrounding the elongated square sleeve 29.

These sleeves and adjacent parts being composed of hard metal, the circular sleeves may turn on the square sleeve within, or the ears 33 may turn on the circular sleeves, without undue friction or wear. For a door of four sections only three hingings are needed, so the bottom and top hanger bearings 27 need not be identical with the bearings 28.

The projecting ends of each horizontal axle 30, beyond the sides of the door, are arranged to carry the sliding or rolling elements engaging in the tracks 14. The following arrangement is shown whereby the positions of the successive sliding elements conform with the inclined setting of the track 14. At each end of each axle is a head or sliding disk 35, fixed on the axle against rotation, for example by reason of the square form thereof.

For purposes of distinction the five sliders or disks 36 are marked 36^a to 36^e respectively on Figs. 1, 2, 3, 6, and 7. Each disk may be machined, or may be built up as in Fig. 8 of two stamped metal pieces, welded or riveted together, and presenting preferably a concave or cupped rim 37. To reduce friction the rim is surrounded by a rotatable ring or tire 38, which also may be concave, with a series of bearing balls 39 located between the disk rim and the tire. The several tires are intended to engage and roll along the track stretches 14, 15, and 16.

As already stated, the several supports or hanger bearings 27 and 28 are of substantially similar construction to the extent that the several axles 15 30 are in alignment in a plane parallel to the inner face of the door. This is not necessarily true of the topmost bearing, since it might be located somewhat higher than shown, opposite a curved portion of the track. In any case the several 20 axles 30 are out of any alignment parallel with the track.

The several pairs of sliders or heads however, although all of substantially equal diameter, are mounted on the respective axles in varying positions, mostly eccentric, so that their centers or axes of rotation are in a common plane parallel to the track when the door is closed. This result is effected by providing a different relation between the respective disks 36 and the successive axles 30. This varying relation is well shown on Fig. 1 wherein the third or middle disk 36^c is shown concentric with the axle 30, whereas the disk 36^b below it is offset relatively outwardly, and the disk 36^a at the bottom is offset further outwardly; while the disk 36^d above the middle one is offset inwardly with respect to the axle, and the topmost disk 36^e is offset still further inwardly. Such varying eccentricity renders the plane of the sliding or rolling centers parallel 40 to the track as stated.

While this arrangement might be secured by the manufacture of different disks of three or more kinds, each with a square axle hole as required, preferably a composite disk is provided, 45 as shown in Fig. 9, having a first or peripheral square hole 41 adapted both for the extreme lower and upper axles, an intermediate hole 42 adapted for the intermediate axles and a central hole 43 for the middle axle. In process of assembling and 50 erecting the door therefore it is only necessary to provide five pairs of identical disks or heads 36 as shown in Figs. 8 and 9, and place each pair correctly upon the respective axles. A square apertured block adjustable radially in the disk 36 or head could be used with like effect.

When the axles with their heads and tires have been assembled with the door, and the heads set into the tracks, the tracks at the two sides have only to be adjusted, by the nuts 21, while the door is closed, to bring the door snugly to the jamb at each side, the upper track stretch being then similarly or otherwise mounted on the ceiling beams. As the door is lifted to open it the 55 tracks draw it away from the jambs, facilitating the movement. A small variety of parts affords the complete structure, minimizing cost of manufacture and erection.

A sectional door construction has thus been disclosed embodying the principles of the invention, but as many features of construction, arrangement and design may be variously modified without departing from such principles, it is not intended to limit the invention to such features 75

except to the extent set forth in the appended claims.

I claim:

- 5 1. A construction for sectional doors openable upwardly and inwardly from closed position, comprising, in combination, a substantially vertical door jamb against which the door contacts when closed, a track spaced inwards of the jamb and inclined upwardly relatively away from the door is closed.
- 10 2. A construction as in claim 2 and wherein the hanger bearings and axles constitute hinge members cooperating with complementary hinge members for articulating the door sections.
- 15 3. A construction for sectional doors openable upwardly and inwardly from closed position, comprising, in combination with opposite substantially vertical door jambs against which the door sides contact when closed, a track spaced inwards of each jamb and inclined upwardly away from the jamb and thereabove curved and extended inwardly, and a door comprising a plurality of articulated horizontal sections adapted to shift while guided by said track for opening and closing the door; each door section having a series of hanger devices each consisting of the following, a pair of bearings fixed to a door section, an axle arranged horizontally in said bearing pair and held against rotation and projecting at both ends beyond the sides of the door, each such projecting axle-end having a head or disk fixed thereon against rotation and adapted to engage and travel along said track; the said bearings being of such similar dimensions that the axes of the several axles lie substantially in a common plane parallel to the closed door, and the several pairs of non-rotatable heads being of substantially equal diameter but mounted on the respective axles in varying positions such that their centers lie in a common plane parallel to the track when the door is closed.
- 20 4. A construction for sectional doors openable upwardly and inwardly from closed position, comprising a substantially vertical door jamb against which each side of the door fits when closed, a track spaced inwards of each jamb and inclined upwardly relatively away from the jamb and thereabove extended inwardly, and a door comprising a plurality of articulated horizontal sections adapted to shift along guided by said track for opening and closing the door; each door section having at least one hanger device consisting of a pair of bearings fixed to the section, an axle slidable horizontally in said bearing pair but held therein against rotation and projecting beyond each side of the door, each such projecting axle-end having a circular disk thereon fixed against rotation and a tire on each disk adapted to engage and travel along said track; the said bearings carrying the several axles with their axes at varying distances from the plane of the tracks,
- 25 5. A construction as in claim 2 and wherein each bearing has a square hole, with a square sleeve therein in which the square axle slides, and a complementary hinge part rotatable on said axle or sleeve.
- 30 6. A construction as in claim 4 and wherein each bearing has a square hole, with a square sleeve therein in which the square axle slides, and a complementary hinge part rotatable on said axle or sleeve.

LE ROY HOWARD KIESLING. 50
